UNITED STATES PATENT OFFICE

ALEXANDER H. DREUX, OF BUFFALO, NEW YORK, ASSIGNOR TO F. N. BURT COMPANY,
LIMITED, OF TORONTO, CANADA, A CORPORATION OF ONTARIO, CANADA

PAPER BOX

Application filed April 9, 1926. Serial No. 100,780.

This invention relates to boxes and box elements made of paper materials and, with respect to its more specific features, to boxes for containing face powder and like material and having an inner drum in which the powder is directly contained and protected preliminarily to being dispensed.

One of the objects of the invention is the provision of a practical box of the character referred to, of simple structure, which is strong and durable and which retains the powder efficiently although permitting ready access thereto.

Another object of the invention is the provision of an efficient box of the character referred to having a frangible cover and from which the cover may be torn or severed quickly and conveniently along a clean line of separation so as to leave the box in condition presenting a neat and attractive appearance.

Another object of the invention is the provision of a practical box of the character referred to to which a closure may readily be applied without danger of fracturing the frangible cover overlying the contents of the box.

Other objects of the invention will be in part obvious and will in part appear hereinafter.

The invention accordingly comprises an article of manufacture possessing the features, properties, and the relation of elements which will be exemplified in the article hereinafter described and the scope of the application of which will be indicated in the claims.

For a fuller understanding of the nature and objects of the invention reference should be had to the following detailed description taken in connection with the accompanying drawing, showing a box in perspective and partly in section, the thickness of some of the parts being exaggerated for the purpose of clearer disclosure.

Referring now more specifically to the embodiment of the invention illustrated in the drawing, the numeral 1 indicates the body of the box. The preferred shape of the box is cylindrical, as illustrated, and the body 1 is composed of paper coiled into several plies,

which become adhesively joined together, the opposite edges of the body being subsequently inwardly folded or crimped, to provide annular beads 2 and 3, one of which beads is inturned sufficiently to provide an underlying surface 4 to assist in retaining a closure member. Within the cylindrical body 1 is a drum composed of the cylindrical flange 7 and the head, or cover, 8, the head 8 being a readily tearable sheet of paper transversely disposed in the box and providing a frangible cover for the contents of the drum, such as face powder. The flange 7 may also be composed of a strip of paper coiled into a plurality of adhering plies into cylindrical form and closely fitting the interior of the body 1 between the beads 2 and 3. Also the drum may be glued to adhere to the body 1.

At the open end of the drum opposite the head 8, is a paper annulus, or ringlike member 9, which partly closes said end, and may be composed of two cardboard plates 10 and 11 adhesively connected together. These plates abut the inner face of the body 1, and underlie the flange 7 and are held against said flange by the bead or crimp 3. The inner plate 10 extends beyond the inner end of the plate 11 thereby providing a recess or groove for the reception of a closure member 12, which latter may be a cardboard disk of a size to close the opening in the annulus 9 and be received in the recess on the seat provided by the member 10. The closure 12 may be secured to the annulus 9 by glue or other suitable adhesive when secure attachment is desired.

The numeral 13 indicates a second annulus which is disposed exteriorly of the drum and is seated on the drum in the region above the flange 7. One edge of the annulus, or ring 13, abuts the body 1 beneath the bead 2, the annulus 13 extending inwardly and projecting beyond the inner face of the flange 7 so as to overlie the marginal portion of the frangible head 8 which is not directly supported by the flange 7. In the embodiment illustrated the inwardly projecting portion 20, of the annulus 13 is adapted resiliently to coact with the bead 2 to retain therebetween a second closure member 14.

of dislike form, the edges of the disk being adapted to underlie the surface 4 of the bead and to abut said bead, when the closure member 14 is seated on the projecting portion of the annulus 13. The projecting portion of the annulus 13, associated as described, provides a stiff, resilient member or tearing blade, against the circular edge 15 of which the material of the head 8 may be manipulated to effect a clean tear when it is desired to sever the head 8. The central portion of the frangible cover, or head 8, is exposed through the annular tearing blade referred to so that upon removal of the closure 14 access is readily had to the cover 8.

In usual practice before the box is filled with powder, the closure 12 is held to its seat in the recess of the ring 9 by close contact of its edge with the edge of plate 11. 20 In this condition and with the closure 14 in place, the box may be shipped from the manufacturer to the filler. By removing the bottom closure 12, the drum may be filled with face powder, or any other material. 25 Thereupon the closure 12 is securely glued in place to close and seal the bottom of the drum. In dispensing, the top closure 14 is lifted and removed by its tab 16, of cotton, silk, or the like, glued to the under face 30 of the closure. After removal of closure 14 the frangible cover 8 may be punched by the fingers, or slitted, or otherwise broken, whereupon each of the broken cover parts 35 may be pressed against the relatively thin edge 15 of the annulus 13 with a tearing movement, on grasping the free edges of the broken parts. The result will be a clean tear against the annulus 13 as a tearing blade. Thus the entire portion of the 40 cover 8 within the circle embraced by the edge 15 may be easily and quickly removed with the production of a clean line of severance along the edge 15, and maximum exposure of powder will thus be obtained. 45 When the box is not in use the closure 14, which is sufficiently resilient, as provided by a flat disk of cardboard, is pressed or snapped past the bead 2 onto its seat on the ring 13. The bead 2 may also yield somewhat to permit passage of closure 14 to and from its seat. When in place the closure 50 14 will be supported on the projecting portion of the ring 13 with the edge of the closure underlying the surface 4 of said bead, and in contact with said bead.

The ring, annulus or tearing blade 13, is gripped between the bead 2 and the drum and, it will be seen, is above, or outside the drum. It intervenes the bead 2 and the cover 8 and it also is between the closure 14 and the cover 8 adjacent the side of the box. The ring 13 therefore serves to guard and protect the paper cover 8 from injury which would result by pressure of the inner edge 60 of the bead 2 thereagainst, and it also spaces

the closure 14 from the cover 8, so that in applying said closure, central flexure thereof is not apt to injure the cover 8. The relatively thin paper cover 8 is glued to the sides of the flange 7 as indicated at 17, and assumes stretched condition across the flange by contraction on drying. The ring 13 lies in the space between the bead 2 and the drum, and the bead 2 cooperates to hold the ring closely against the head, or cover 8, said bead lapping onto the outer face of said ring. 70

Thus by the construction described are accomplished among others, the objects hereinbefore referred to. 80

Since certain changes may be made in the article and different embodiments of the invention could be made without departing from the scope thereof, it is intended that all matter contained in the above description or shown in the accompanying drawing shall be interpreted as illustrative and not in a limiting sense. 85

Having described my invention, what I claim as new and desire to secure by Letters Patent, is:

1. A box including a body and an inner drum, the drum being open at one end and closed at the other end by a frangible sheet of paper, an annulus partly closing the open end of said drum, an annulus supported on said drum and exposing the central part of said sheet, the body of said box having a fold providing a bead which laps onto the outer face of the last mentioned annulus and resiliently coacts to hold it against said sheet. 95

2. A paper box having a transversely disposed sheet providing a frangible cover for the contents of the box, an annular tearing blade held in position outside said cover and through which said cover is accessible, the body of said box being folded to provide a bead adapted to cooperate to hold said blade close to said cover, said blade being resiliently acting and extending inwardly to provide a seat for a closure member, and a removable, resilient, closure member supported by said seat, with its edge in contact with said bead, said blade being between said closure member and said cover adjacent the side of the box. 105 110

In test only whereof I affix my signature.
ALEXANDER H. DREUX.
